UNITED STATES PATENT OFFICE.

WALTER BIRD, OF MORRILLTON, ARKANSAS.

DASHER MECHANISM FOR CHURNS.

1,420,955.

Specification of Letters Patent. Patented June 27, 1922.

Application filed July 30, 1921. Serial No. 488,601.

To all whom it may concern:

Be it known that I, WALTER BIRD, a citizen of the United States, residing at Mor-
rillton, in the county of Conway and State
5 of Arkansas, have invented certain new and
useful Improvements in Dasher Mechanisms
for Churns, of which the following is a speci-
fication, reference being had to the accom-
panying drawings.

10 This invention relates to certain improve-
ments in dasher mechanisms for churns and
it is an object of the invention to provide a
novel and improved mechanism of this gen-
eral character whereby the agitators and
15 shafts comprised therein may be removed
and applied with convenience and facility
to facilitate the cleansing of the mechanism.

Another object of the invention is to pro-
vide a novel and improved mechanism of this
20 general character including a clamp adapted
for attachment to a churn body together
with means whereby the mechanism proper
is supported by said clamp when in applied
position.

25 An additional object of the invention is to
provide a mechanism of this general char-
acter including agitating blades arranged on
a pitch whereby the milk, during a churning
30 operation is forced downwardly by said
blades and wherein said blades are provided
with perforations for aerating the milk.

The invention consists in the details of
construction and in the combination and ar-
rangement of the several parts of my im-
35 proved dasher mechanism for churns where-
by certain important advantages are attained
and the device rendered simpler, less expen-
sive and otherwise more convenient and ad-
vantageous for use, as will be hereinafter
40 more fully set forth.

The novel features of my invention will
hereinafter be definitely claimed.

In order that my invention may be the
better understood, I will now proceed to de-
45 scribe the same with reference to the accom-
panying drawings, wherein:

Figure 1 is a view partly in section and
partly in elevation illustrating a dasher
mechanism for churns constructed in ac-
50 cordance with an embodiment of my inven-
tion.

Figure 2 is a view in top plan of the exten-
sion or arm carried by the upper portion of
the post or standard,

Figure 3 is a fragmentary view in elevation 55
illustrating in detail the means for main-
taining the shafts in applied position,

Figure 4 is a sectional view taken substan-
tially on the line 4—4 of Figure 1,

Figure 5 is a view partly in section and 60
partly in top plan taken through the lower
portion of the shafts above the blades,

Figure 6 is an enlarged fragmentary sec-
tional view taken substantially on the line 65
6—6 of Figure 5,

Figure 7 is an enlarged fragmentary view 70
partly in section and partly in elevation
illustrating in detail the adjustable flange
carried by one of the arms of the clamping
member,

Figure 8 is a sectional view taken sub-
stantially on the line 8—8 of Figure 7, and

Figure 9 is a fragmentary view partly in
section and partly in top plan illustrating
75 the bracket carried by the upper portion of
the post or standard and which is provided
with the stub shaft for the operating gear.

As disclosed in the accompanying draw-
ings, C denotes a clamp member comprising
three substantially equi-distantly spaced 80
arms 1 having their inner or adjacent end
portions integrally formed with a central
body or plate 2. The outer extremities of
two of the arms 1 are provided with depend-
85

ing flanges 3 adapted to overlie the upper
portion of a churn body when the device is
in applied position. The outer end portion
of the third arm is provided with an out-
standing extension 4 continued by a threaded
shank 5. The extension 4 is angular in 90
cross section and is freely disposed through
an opening 6 produced in the upper portion
of a flange 7. The upper portion of this
flange 7 is also provided with an inwardly
disposed wing or web 8 overlying and con-
95

tacting with the upper face of the adjacent
arm 1. Threaded upon the shank 5 is a hold-
ing nut 9. The flange 7 is adjustable or re-
movable lengthwise of the extension 4 so
that the clamping member C may be oper-
atively engaged with churn bodies of differ-
ent sizes. The nut 9 is adapted to coact with
100 the flange 7 to maintain the member C firmly
in applied or working position.

The central body or plate 2 adjacent the 105
inner end of one of the arms 1 is provided
in its upper face with a pocket or depression
10, and at the central portion of said de-

pression with an opening 11. The lower end portion of an upstanding standard or post 12 is adapted to snugly seat within the pocket or depression 10, and the said end 5 portion is provided with an outstanding threaded shank 14 which extends through the opening 11, and engaged with the shank 14 is a clamping nut 15 coacting with the under face of the central body or plate 2 10 whereby the standard or post 12 is effectively anchored in working position yet can be readily removed when the occasions of practice may require.

The upper end portion of the standard or 15 post 12 is provided with an extension arm 16 disposed in a direction away from the arm 1 with which is aligned the pocket or depression 10, and the upper or free end portion of said extension or arm 16 is provided 20 with a recess or notch 17 which substantially registers with a notch or recess 18 produced in the central body or plate 2 at the junction of the remaining two arms 1. The post or standard 12 at its upper part or below the 25 extension or arm 16, is provided with a substantially L-shaped bracket 19, the foot *a* of which being positioned beyond the outer end of the extension or arm 16. The foot *a* is provided with an outstanding stub shaft 20 30 extending in the same general direction as the extension or arm 16 and is adapted to have mounted thereon a face gear 21 of desired diameter. The gear 21 is maintained in applied position upon the stub 35 shaft 20 through the instrumentality of a pin 22 disposed through the stub shaft 20 outwardly of the applied gear 21 or in any other manner preferred. The gear 21 is provided with a handle 23 or the like where- 40 by the same may be conveniently rotated.

24 denotes an elongated tubular shaft having affixed to one end portion a gear 25 which, when the shaft 24 is in applied position, is adapted to mesh with the face gear 45 21 from below. Fixed to the opposite or lower end portion of the shaft 24 are the diametrically opposed blades 26, the pitch of each of such blades being such that when the device is in working position and the shaft 50 24 is rotated, said blades will force the milk or other liquid downwardly.

Disposed through the shaft 24 is a second shaft 27 of a length to extend beyond the opposite ends of the shaft 24. One end portion 55 of the shaft 27 has fixed thereto a gear 28 which, when the device is assembled, meshes with the upper portion of the gear 21 so that upon rotation of the gear, the shafts 24 and 27 will be rotated in unison 60 but in a reverse direction. The opposite or lower end portion of the shaft 27 has fixed thereto the diametrically opposed blades 29, the pitch of each of these blades also being such to force the milk or other liquid downwardly during a working operation. Each 65

of the blades 26 and 29 is provided with a series of perforations or openings 30 whereby the milk, during a churning operation, is aerated.

When the device is assembled, the upper portion of the shaft 24 is received within the recess or notch 18 in the central body or plate 2, while the upper portion of the shaft 27 is received within the notch or recess 17 in the extension of arm 16 with the gear 28 70 engaging said extension or arm 16 from above. When in this position, the central portion of the blades 26 has contact with the central portion or hub 31 of the blades 29 whereby the downward movement of the shaft 24 is limited. The lower end portion of the tubular shaft 24 is provided with an internal packing 32 surrounding the shaft 27 to prevent the milk or the like from rising within the shaft 24. 80

The central body or plate 2 at opposite sides of the recess or notch 18 has disposed therethrough the openings 33 and insertible through said openings 33 are the pins 34 carried by the opposite end portions of a holding member 35. The pins 34 are disposed through the openings 33 from above and one of said pins 34 is of a length greater than the other. Disposed through the lower or free end portion of the longer pin 34 is a 90 cotter pin 36 or the like providing a stop whereby the said longer pin 34 cannot be entirely drawn through the coacting opening 33 but to an extent to disengage the shorter pin 34. When the pins 34 are disposed 95 through the openings 33, the member 35 serves to hold the shaft 24 within the notch or recess 18.

From the foregoing it is believed to be readily understood that my improved agitating mechanism may be readily and conveniently assembled when desired and also conveniently disassembled so that the parts may be separated to facilitate the cleansing thereof. 100

From the foregoing description it is thought to be obvious that a dasher mechanism for churning constructed in accordance with my invention is particularly well adapted for use by reason of the convenience and facility with which it may be assembled and operated, and it will also be obvious that my invention is susceptible of some change and modification without departing from the principles and spirit thereof and for this 110 reason I do not wish to be understood as limiting myself to the precise arrangement and formation of the several parts herein shown in carrying out my invention in practice except as hereinafter claimed. 115

I claim:

1. A mechanism of the class described comprising a supporting member, a post mounted thereon provided with a laterally extending arm, said arm having a recess, 120

said member being provided with a recess, a bracket carried by the post inwardly of the arm, an operating member supported by the bracket, a tubular shaft seating within the 5 recess of the member and in driven connection with the operating member, a shaft disposed through the tubular shaft, the upper end portion of the shaft seating within the recess of the arm, an operating member carried by said second shaft and resting upon the arm, said operating member being in driven connection with the first named operating member, said second shaft extending below the tubular shaft, a holding member 10 carried by the first named member and adapted to close the recess in said first named member for holding the shafts therein, 15 member carried by the first named member and adapted to close the recess in said first named member for holding the shafts therein.

2. A mechanism of the class described comprising a supporting member, a post mounted thereon provided with a laterally extending arm, said arm having a recess, said member being provided with a recess, a bracket carried by the post inwardly of the arm, an operating member supported by the 20 bracket, a tubular shaft seating within the recess of the member and in driven connection with the operating member, a shaft disposed through the tubular shaft, the upper end portion of the shaft seating within the recess of the arm, an operating member carried by said second shaft and resting upon the arm, said operating member being in driven connection with the first named operating member, said second shaft extending below the tubular shaft, a holding member 25 carried by the first named member and adapted to close the recess in said first named member for holding the shafts therein.

2. A mechanism of the class described comprising a supporting member, a post mounted thereon provided with a laterally extending arm, said arm having a recess, said member being provided with a recess, a bracket carried by the post inwardly of the arm, an operating member supported by the 30 bracket, a tubular shaft seating within the recess of the member and in driven connection with the operating member, a shaft disposed through the tubular shaft, the upper end portion of the shaft seating within the recess of the arm, an operating member carried by said second shaft and resting upon the arm, said operating member being in driven connection with the first named operating member, said second shaft extending below the tubular shaft, a holding member 35 carried by the first named member and adapted to close the recess in said first named member for holding the shafts therein, said holding member being provided at its opposite end portions with laterally directed pins, 40 the first named member being provided at opposite sides of the recess therein with openings through which said pins are insertible, one of said pins being longer than the other, and means carried by the longer pin to prevent the complete withdrawal thereof through the coacting opening in the first named member.

In testimony whereof I hereunto affix my signature.

WALTER BIRD.
